CLAIM

The ornamental design for a truck bed closure, substantially as shown and described.

DESCRIPTION

FIG. 1 is a side elevation view of a truck bed closure showing my new design;

FIG. 2 is a rear elevation view thereof;

FIG. 3 is a front elevation view thereof;

FIG. 4 is a top plan view thereof; and

FIG. 5 is a bottom plan view thereof.

The broken lines in the drawing are for illustrative purposes only.

The side opposite to that shown in FIG. 1 is substantially a mirror image thereof.
